UNITED STATES PATENT OFFICE.

VIRGINIA COPLAND, OF WASHINGTON, DISTRICT OF COLUMBIA.

DESIGN FOR AN ERASING-PLATE.

SPECIFICATION forming part of Design No. 26,251, dated November 10, 1896.

Application filed September 24, 1896. Serial No. 606,896. Term of patent 31 years.

To all whom it may concern:

Be it known that I, VIRGINIA COPLAND, a citizen of the United States, residing at Washington, in the District of Columbia, have invented and produced a new and original Design for Erasing-Plates, of which the following is a specification, reference being had to the accompanying drawings, showing a part thereof, and in which—

10 Figure 1 is a face view of a plate, showing my design; and Fig. 2 is a sectional view on about line 2-2 of Fig. 1.

The leading feature of my design consists in a plate having the longitudinally-extended 15 slots A, B, B', B², B³, C, C', and C², and the transverse slots D, E, and F. The slot A extends almost the full length of the plate, while the several other slots are arranged below said slot A, the slots B, B', B², and B³ being 20 alined, and the slots C, C', and C² are alined

and arranged in a plane below the slots B, B', B², and B³. The slot D is arranged between the slots B and B', and the slot E between the slots B' and B², while the slot F is arranged between the slots C and C'. 25

It will be noticed that the slots D, E, and F are parallel and are extended in a direction at right angles to the slots A, B, B', B², B³, C, C', and C².

Above the slot A and adjacent to the edge 30 of the plate I provide a set G of graduations numbered 10 20, &c., as shown.

What I claim is—

The design for an erasing-plate herein shown.

VIRGINIA COPLAND.
